IDENTIFICATION BUTTON

Anita J. Jones, Beverly Hills, Calif.

Application December 17, 1938, Serial No. 246,392

2 Claims. (Cl. 40—10)

This invention is an identification device embodied in the general form of a button.

It is desirable to provide an ornate, sufficiently conspicuous and practical, indicia-protective device for the effective identification of the owner of various articles of personal property which may have been lost. For instance, when one of an expensive pair of gloves is lost the finder can have no reasonable use of the found glove, at least for dress purposes, and ordinarily the finder of such a lost glove, having a fair opportunity and free from expense to himself or herself would gladly return the glove to the rightful owner. And frequently finders of other articles, not of matched type or class, would return the found article if without personal inconvenience.

It is particularly an object to provide a glove identification device incorporative in an usual element of the glove so as to avoid application of an extra or unnecessary element or means aside from usual glove features. Therefore a purpose is to provide an improved button-like or other appropriate form of fastener distinguished by a construction enabling the protective encasement therein of a simple address bearing ticket, sheet or card which may be fairly readily removed by the finder in event of the loss of the glove, or such other article, to which the "finder" as it may be called, is attached.

A further object is to provide a finder device of this type readily embodiable in buttons or fasteners of more or less conventional shape, and having one or another of divers provisions for the attachment of the button or fastener involving the novel identification feature, to the desired article to be so marked as to ownership.

The invention consists of certain advancements in this art as set forth in the ensuing disclosure and having, with the above, additional objects and advantages as hereinafter developed, and whose construction, combinations and details of means, and the manner of operation will be made manifest in the description of the herewith illustrative embodiments; it being understood that modifications, variations and adaptations may be resorted to within the scope, principle and spirit of the invention as it is more directly claimed hereinbelow.

Figure 1 is a perspective of a glove having an applied "finder" identification device, and fastener combination.

Figure 2 is a detail, axial section of the device.

Figure 3 is an axial section of a fastener-stud embodiment.

Figure 4 is a face plan of the top or outer

element of a fastener or button part of the finder.

Figure 5 is a perspective of one form of identification element to be encased in the receiver part of the device.

Figure 6 is an edge elevational view of a basal part of the device adapted for stitching onto a given article.

Figure 7 is an edge elevation of a base part with prongs for attachment.

Figure 8 is a side elevation of an open, hinged type of the device, and

Figure 9 is a side elevation of a detachable, clamp-on embodiment.

There is here provided a simple sheet, card or other member 2 for the application of the indicia as to the address or other notice for the location of the owner of the article, as a glove G, in event that the glove is lost or mislaid, and by which information the person finding the lost article may locate or "find" the owner. This member, 2, is adapted to be compacted or folded to a size to enable it to be securely tucked into the cavity 3 of an outer, hollow button or fastener shell 4 having a constricted mouth 5 at the lower side of the shell for insertion of the identification member 2.

This member is preferably flexible and of resilient material so that it will expand in the cavity and lodge back of the mouth or of the shoulder thereabout.

The shell 4 is suitably relatively movably mounted on a basal or attaching element which, in Figs. 2, 3, 6 and 7 has a threaded neck 7 onto which may be screwed a complementary barrel part 4' of the shell 4, after the address member 2 has been inserted in the shell cavity; the neck 4'; Fig 3 being threaded internally for the base stud 9, and externally for use if desired on internal threads as in Fig. 6. The base member 6 of Fig. 2 is of socket type to be snapped onto a complementary, opposed stud part 8.

The shell 4 of Fig. 3 has its base part 6 provided with a stud 9 to fit a complementary socket, not shown.

The base part 6 of Fig. 6 is adapted for stitching 45 10.

In Fig. 7 the base 6 has prongs 11 for securing.

A modified form of the device is shown in Fig. 8 wherein the container or shell 4 is hinged at 12 to its base part 6 which is suitably securable to the given article. One edge portion of the shell may have a resilient hook 13 to frictionally engage the opposed base edge and hold the shell closed.

55

Another hinged type of the owner finder is shown in Fig. 9 and in which the shell 4 is spring hinged at 14 to normally frictionally grip on the marginal portion of the article so that the finder 5 may be readily removed for use on any of different articles. In this form a securing prong 15 may be used to fasten the shell in place.

In order that the identification purpose of the notice-containing shell 4 may be made instantly observable it is provided with a window opening 16 which may or may not be sealed by a transparency 17.

A person finding such an identified glove or other article will naturally open the shell member 4 and inspect the notice, and in many cases will go to the trouble of notification according to the instruction given on the indicia member 2.

Fig. 2 shows the shell 4 having a neck 4' with a small out turned flange at its bottom. The shell 4 of Figs. 8 and 9 is of the same section as Fig. 2 without threads, but the said neck flange is widened as at 4^b to form a flat leaf with a hinge 12 or 14, as in Figs. 8 and 9.

What is claimed is:

25. 1. A device consisting of a hollow body with an access opening in its bottom, an indicia element insertible into the body through the opening, and a base member having a fastener part

for attachment to a given article and forming a closure for said opening and retaining the said element in the hollow body, and the body and the base member being hingedly connected.

2. In an identification device; the combination comprising a base member having a fastener part for attachment to a given article, a hollow un-encased or coverless body more or less of button form and having a mouth in its bottom and providing for access to the interior and said base member being attached to the bottom of the body for ready opening movement of the latter as to the base and the base constituting the direct closure for the access mouth; the body being adapted to be readily charged when open with a suitable identification means and as readily opened for inspection without mutilation of the body and the base member and the body including attaching means having mutual, temporarily interlocking parts separable by manual effort without use of mechanical appliances and without a resulting permanent distortion of either of the mutual parts; whereby to provide for re-use of the assembly parts, one of said interlocking parts being in the form of a marginal, resilient snap clamp to yieldably grip onto the complementary, other part.

ANITA J. JONES.
